DESIGN FOR A VENDING MACHINE CASING OR THE LIKE

Fairfield W. Hoban, New York, N. Y., assignor to Stewart and McGuire, Incorporated, New York,
N. Y., a corporation of New York

Application August 18, 1938, Serial No. 79,427

Term of patent 7 years

To all whom it may concern:

Be it known that I, Fairfield W. Hoban, a citizen of the United States and a resident of the Borough of Manhattan, in the county, city, and State of New York, have invented a new, original, and ornamental Design for a Vending Machine Casing or the like, of which the following is a specification, reference being had to the accompanying drawing, forming a part thereof.

In the drawing:

The figure is a perspective view of a vending machine casing showing my new design.

I claim:

The ornamental design for a vending machine casing or the like, as shown.

FAIRFIELD W. HOBAN.
